VALVE FOR PRESSURIZED CONTAINERS
 Ralph K. Boyer, Cleveland, and Homer F. Eyerdam,
 Lakewood, Ohio, assignors to Eaton Manufacturing
 Company, a corporation of Ohio
 Filed Nov. 23, 1964, Ser. No. 412,914
 23 Claims. (Cl. 222—402.24)

This invention relates to a dispensing valve for a pressurized container.

This invention will be described in combination with the pressurized container of the so-called aerosol type, it being understood that this invention is applicable to any pressurized vessel or container.

The problem has been to find a valve, that is simply and inexpensively constructed, and easily operated. Many of the valves presently used have a number of complex and intricate parts. Also, each of the parts is susceptible to wear and breakage, and breakage of a part in a container of this type frequently means loss of the contents or inability to utilize the contents. Therefore, it is desirable to produce a relatively simple reliable dispensing valve for pressurized vessels or containers.

To the accomplishment of the foregoing and related ends, said invention, then, consists of the means herein-after fully described and particularly pointed out in the appended claims, the following description and annexed drawings setting forth in detail certain illustrative embodiments of the invention, such disclosed means constituting, however, but a few of the various forms in which the principle of this invention may be employed.

This invention accomplishes this by providing a resilient elongatable valve housing and a valve mounted on a rigid externally accessible elongated valve stem which is reciprocable therein, and which permits fluid under pressure to be released from the container when the stem of the valve is depressed. The fluid, usually normally gaseous, may be the sole material dispensed, or it may be a vehicle or carrier for another material of solid, liquid or gaseous nature, e.g. insecticides, deodorants, hair sprays, etc. The housing and valve are designed to be inserted into a pre-formed opening in a container, often after complete assembly of the metallic portion of the can and after filling with the dispensable material. Filling through the valve is also a common practice where the container and valve are completely assembled prior to filling.

The valve is seated against a valve seat which is formed in the housing. As the stem of the valve is depressed the valve becomes unseated and fluid in the container flows through the housing, between the valve and the valve seat and is released from the container. Depression of the valve stem exerts force against an abutment in the housing causing the resilient housing to elongate. The housing being resilient will assume its original configuration when the force is taken away. The resiliency of the elongated housing provides a means for reseating the valve.

The simple biasing action of the housing replaces the complicated spring valve closure systems of prior valves. The valve and housing are simple and are economically manufactured. The product is designed to reduce the number of working parts as well as simplify the manner in which they operate, and the manner in which they are applied to the metal container.

Briefly stated, then this invention is in a dispensing valve for a pressurized fluid container. This is characterized by a resiliently flexible wall enclosed chamber having a fluid inlet in spaced relation to fluid outlet. An externally accessible valve stem extends into the chamber through the outlet and engages a wall of the chamber. A valve carried by the stem is biased into outlet closing engagement by the wall of the chamber.

2

In the annexed drawings:

FIG. 1 is a perspective view of a portion of a pressurized container showing one embodiment of the valve structure of this invention in combination therewith.

5 FIG. 2 is an enlarged cross-sectional view of the valve structure shown in FIG. 1.

FIG. 3 is an exploded perspective illustration showing the valve and resilient valve housing used in the embodiment of the invention shown in FIG. 2.

10 FIG. 4 is a cross-sectional view showing the resilient housing of FIG. 3 in combination with a bushing which is secured to the opening in the cap of the container.

FIG. 5 is a cross-sectional view of another embodiment of this invention. This particular embodiment is used 15 with pressurized vessels where the pressure is relatively small, e.g. 4 to 20 p.s.i.g.

FIG. 6 is a cross-sectional view of still another embodiment of this invention.

FIG. 7 is a cross-sectional view of still another embodiment of this invention. This embodiment is particularly designed to dispense foods from a container.

FIG. 8 is a cross-sectional view of another embodiment 25 of this invention, i.e. a resilient valve particularly designed for use in a conventionally designed propane gas torch.

FIG. 9 is a fragmentary view in cross-section of a container including a modified valve structure in accordance with this invention.

FIG. 10 is a fragmentary view in cross-section of a container including another modified valve structure in accordance herewith. Similar or corresponding parts in the figures have corresponding numbers.

FIG. 11 is a fragmentary cross-sectional view of another embodiment of this invention.

35 Referring more particularly to FIGS. 1-4 of the annexed drawings, there is shown a conventional metallic pressurizable container or dispenser, generally indicated at 10. The container 10, as manufactured, has an open annular rim portion 11. A cap portion 12 is designed to be secured or rolled onto the rim portion 11 to seal the container 10. Cap 12 may have formed therein, an annular recess or depression 13 which extends into the interior of the container 10. As hereinafter described, the depth of the recess 13 may be varied to accommodate a variety 45 of predetermined container pressures. Centrally disposed in the cap 12 or in the bottom of the recess 13, is an opening 14 (FIG. 4). Spaced around the opening 14 there may be provided one or more smaller holes, e.g. hole 15 (FIG. 2) which serve as excessive pressure relief ports.

50 A resilient, elongatable valve housing, generally indicated at 16, and generally formed of a fluid resistant elastomer, e.g. neoprene, is designed to be inserted through the opening 14 of the cap 12. As seen in FIG. 3, the housing 16 is composed of substantially cylindrical portions 17 and 18 of disparate sizes. When inserted 55 in the opening 14, the cylindrical or plug portion 17 preferably tightly fits into the recess 13. The outer annular surface of the cylindrical portion 17, compressively engages the inner annular surface of the walls which form the recess 13. Cylindrical portion 18 has a diameter 60 larger than opening 14 and is adapted to be forced therethrough and to extend into the container 10. For ease in assembly with the opening 14 a locating ring 14a (FIG. 6) may be provided to give visual confirmation of proper 65 location of body 18 therein. The sides of the housing 16 adjacent the opening 14 are compressed inwardly effecting a pressure withstanding seal with the marginal edges of the opening 14 and simultaneously "locking" the valve structure to the container 10.

70 A rim 19 is formed in the housing 16 between the abutting portions 17 and 18, and delineates an annular recess 20 radially inwardly thereof. A centrally disposed pas-

sageway or bore 21 extends from the outside of the resilient housing 16 and communicates with a fluid receiving chamber 22. In the preferred embodiments, bore 21 continues to provide in the opposite wall of chamber 22, an abutment 24. An annular valve seat 23 is formed in the fluid pocket or chamber 22 adjacent the outlet passageway 21. In the embodiment of the invention shown in FIGS. 2 and 6 an inlet passageway 25 communicates between the fluid pocket or chamber 22 and the exterior of the valve structure which extends inside of the container 10.

An elongated valve stem or plunger, generally indicated at 30, is externally accessible and reciprocable in the housing 16. The valve stem 30 includes an elongated, substantially cylindrical valve stem portion 31 which is movable, and is sealingly engaged by the side walls of the passageway 21 of the resilient housing 16. Intermediate the extremities of the valve stem 30 there is provided a valve 34 which coacts with valve seat 23 to control fluid flow. When the valve 34 is in a closed position, the valve stem 31 has its extremity 32 resting against the abutment 24 and resiliently biased by the valve body 16 into closing relation with outlet 21. The other extremity 33 of the valve stem 31 may protrude beyond the cap 12 of the container 10 to receive a dispensing and valve operating button 42, or be recessed therein for external access by structure such as shown in FIG. 7. When the stem 31 is depressed, the resilient housing 16 becomes elongated and the valve 34 becomes unseated with respect to the valve seat 23, permitting fluid to be forced from the container 10. The biasing action of the elongated resilient housing 16 forces the valve stem 30 to return valve 34 to its normally closed position.

In the embodiment of the invention shown in FIG. 2 the valve stem 30 has a centrally disposed axial bore 35 which is discontinuous adjacent the valve 34. A radial port or bore 36 adjacent the high pressure side of the valve 34 communicates with the valve stem passageway or bore 35a and the fluid pocket or chamber 22. A radial port or bore 37 adjacent the low pressure side of the valve 34 communicates with the valve stem passageway 35 and the fluid chamber 22 when the valve 34 is unseated. The stem portion 38 adjacent the valve 34 in which the radial port 37 is located, is of smaller diameter than the walls of the passageway 21 and forms an annular fluid passageway 40 for exiting fluid from chamber 22.

In the embodiment of the invention shown in FIGS. 2 and 4, a tube 41 passes through the passageway 25 of the housing 16 and is secured to the end 32 of the valve stem 30 and communicates with the passageway 35a. Tube 41 extends in the usual fashion to the bottom of the container to facilitate upright container discharge. When the valve is depressed, fluid in the container is forced through the tube 41 into the inlet passageway 35a through radial port 36 and into the fluid pocket 22. The fluid is then forced past the valve 34 into the annular recess 40, through radial port 37 and into the passageway 35. The button or spray nozzle 42 is rotatably and slidably secured to the stem portion protruding beyond the cap 12. The nozzle 42 is designed to abut the shoulder 43 which is integral with the valve stem portion 31. An aperture 44 in the nozzle 42 provides for fluid release from cap chamber 50 which, in turn, communicates with the fluid passageway 35 of the stem 31. The fluid is forced from the passageway 35 through the aperture 44 into the atmosphere.

As previously indicated the valve and resilient valve housing are designed to relieve excess pressure in the container. Referring particularly to FIG. 2, excess pressure in the container will force fluid (gas or liquid) through the holes spaced around the opening 14 into the annular recess 20 in the shoulder 19. The fluid is forced from the annular recess 20 out into the atmosphere between the compressively engaged surfaces of the cylindri-

cal portion or plug adapter 17 of the resilient housing 16, and the cylindrical walls 45 which form the annular recess 13. It is readily seen that the extent of surface contact between the resilient housing and the walls of the recess 13 can serve as a means for regulating the amount of pressure in the container. This is graphically illustrated in FIGS. 2, 4, 5, 6, and 7. The depth of the recess 13 is variable with the pressure requirements of the contents of the container. Containers having relatively greater pressures use an embodiment of the invention as shown in FIGS. 2, 4, and 7.

In the embodiment of the invention shown in FIG. 4, the surface contact between the resilient housing and the walls of the recess are increased by securing to the cap, a bushing or collar 46 which extends from the cylindrical walls forming the recess 13. The depth of the recess 13 seen in FIG. 6 is approximately one half the depth of the recess 13 of FIGS. 2, 4, and 7. Thus, this combination may be used with a container wherein there is relatively less fluid pressure.

In the embodiment of the invention shown in FIG. 5, there is no annular recess 13. This combination between the opening and the housing is particularly adapted for a relatively low pressure container, e.g. 4-20 p.s.i.g. In this embodiment, the end portion or plug adapter 17 of the housing 16 is mounted atop the annular flange portion 47 of the cap 12. A similar opening 14 is disposed in the flange portion 47. The excess fluid pressure forces air through similar holes 15 in the flange portion 47 into a similar recess 20 in the underside of the end portion 17. The gas or liquid is then forced from the annular recess 20 into the atmosphere between the abutting annular portion 48 of the resilient housing 16 and the flange 47 of the cap 12. Thus there is provided a safety feature in the devices of this invention which permits regulation of the escape pressure to accommodate a variety of pressurized fluids.

The embodiment of the valve shown in FIG. 5 differs from that shown in FIG. 2 in that the valve stem is solid. Fluid is not forced into the fluid pocket 22 through passageways in the valve stem, but rather through an inlet port 49 in the side walls of the fluid pocket 22 adjacent the valve seat 23. In this particular embodiment of the invention, the container must be tilted upside down if all the contents are to be used because the inlet port 49, through which the contents must flow, is located near the top of the container.

The embodiment of the valve shown in FIG. 6 is particularly adapted for use as a two way valve, in which fluid under pressure may be forced into a container from a source under higher pressure than the contents of the container. The valve stem is bored in a manner similar to that shown in FIG. 3 and it operates in a manner corresponding to the valve shown in FIG. 2. Valve stem 30 also includes a recessed portion 38 including the opening of radial bore 37 which in combination with opening 21 in the housing 16 forms an auxiliary chamber 40 on the low pressure side of the valve 34. The means for permitting the fluid to flow from the outside of the container into the pocket 22 in order to refill, or fill after assembly of the valve to the can, the container is an elongated slit or slits, e.g. slit 50a in the walls of the fluid pocket 22. Although some fluid will flow into the container in a reverse manner through the continuation of axial bore 35, this path tends to be too restricted for rapid refill and the slit will pass the major portion of incoming fluid. When the dispensing valve is closed the slit is closed by the internal pressure of the container acting to compress the side walls of chamber 22 and fluid will not flow from inside the container into the fluid chamber 22 through the slit. When the valve stem 30 is depressed by a suitable fitting (not shown) in the filling line, the action causes the resilient housing 16 to elongate. The higher pressure in the filling line causes the slit 50a to open, and fluid may be forced through the valve stem

passageway 35, around the valve seat 23 and into the container through the now elongated or open slit 50a. Thus this valve structure is adaptable to refillable dispensing vessels or containers.

The embodiment of the invention shown in FIG. 7 is particularly adapted for dispensing foods from a container, e.g. cake frosting. The resilient housing 16 is similar to that used in the embodiment shown in FIG. 2 with the following exceptions. There is no passageway 25 extending from the fluid pocket into the container. Instead, an inlet port 51 is located in the side of fluid chamber 22 adjacent the valve seat 23. A second valve seat 52, in spaced relation to the valve seat 23, is located in the passageway 21 adjacent the outer extremity 56 of the resilient housing 16. The valve stem 31 is similarly slidable in the passageway 21 of the housing 16. When the valve 24 is in a closed position, the outer end of the valve stem 31 is flush with the extremity 56 of the housing 16. An auxiliary valve 57 integral with the valve stem 31 engages the valve seat 52 to seal fluid in the outlet chamber 61 from exposure to air which in the case of food product dispensing is most important. The purpose of the dual valve seating arrangement is to keep as little as possible of the contents of the container from being exposed to the atmosphere, thus reducing or substantially eliminating any spoilage of the contents in or near the outlet of the container.

A resilient dispensing nozzle 58 is removably secured to the dispenser cap 12. When secured thereon, the nozzle 58 has a passageway 59 which extends from the outside of the nozzle 58 to a point in line and adjacent to the passageway 21 of the resilient housing 16. The stem portion 60 in the passageway 21, is smaller in diameter than the passageway 21 thus forming an annular space or outlet chamber 61. When the resilient dispensing nozzle 58 is depressed, the cylindrical walls 62 which form a portion of the passageway 29, coact with the end of the valve stem 30 to unseat the valves 57 and 34 allowing fluid, under pressure to flow through the inlet port 51 into the fluid chamber 22, around the valve 34 into the annular space or outlet chamber 61, and around the valve 57 into the passageway 59 of the spray nozzle 58, and out into the atmosphere. The beveled or chamfered lower edge 63 of the cylindrical wall member 62 tends to spread the exit 64 to permit freer passage of the contents by the valve stem extremity 65 and form a seal therewith. Fluid, or food contents, flows past valve seat 52 through exit 64 and notch 66 into exit passageway 59. Upon release, the exit 64 tends to close around stem extremity 65 and the movement of valve stem 30 upwardly due to the biasing action of resilient housing 16 acting through abutment 32 cleans perishable material out of the valve structure and forces it to the outside of the container body where it can be cleaned off by washing, for example, when the cap 58 is removed. The rolled rim 12a may be so disposed that the external extremity of plug 17 is flush with the top of the container to facilitate cleaning.

Referring more particularly to FIG. 8, there is shown a conventionally designed propane torch 70. A metal closure cap 71 with a hole 72 therein, seals the end of the container 70.

A resilient valve housing 73, inserted in the hole is compressively engaged therein intermediate its extremities. An outlet passageway 74 extends into the housing 73, and communicates with fluid pocket or chamber 75. A plurality of inlet ports, e.g. ports 76 and 77 in the walls of the housing 73, permits fluid to flow into the fluid pocket 75 from inside the container 70. A valve seat 78 is formed in the pocket 75 adjacent the outlet passageway 74.

A valve stem 79, slidable in the passageway 74, extends into the pocket 75 and rests against an abutment 81, formed in the pocket 75 opposite the valve seat 78. The

other extremity 82 of the valve stem 79, protrudes from the passageway 74. The valve stem or plunger 79 has secured thereto, and integral therewith, a valve 83. The valve 83 is biased against the valve seat 78 by the resilient housing 73. When the valve stem 79 is depressed as by attachment of the torch fitting 85, the resilient housing 73 elongates and the valve 83 becomes unseated, and fluid will flow from the pocket 75 into torch fitting or nozzle 85 where it is then controlled by valve 87. When the force, depressing the valve stem 79, is removed the resiliency of the housing 73 will return the valve 83 to its closed position against the valve seat 78.

A conventionally designed adapter 84 is secured to the cap 71. Adapter 84 serves as an abutment for a portion 74 which tightly fits around valve stem extremity 82 and forms a pressure withstanding seal therewith to prevent loss of gas under pressure when valve 83 is unseated, and also serves to prevent extrusion of the valve housing under elevated pressures. The upper extremity of the valve stem includes an axial bore 35 and a radial port communicating therewith on the low pressure side of valve 83 for letting gas out of the container for delivery to the torch nozzle 85. Nozzle 85 is threadedly secured to the free extremity of the adapter 84. Nozzle 85 has a portion thereof or a pin, indicated at 86, compressively engaging the valve stem extremity 82 to force the valve 83 away from the valve seat 78. Fluid is thus forced into the nozzle 85. A conventionally designed valve 87 in the nozzle 85 regulates the flow of fluid therethrough.

The valve housing 73 includes means for releasing excess pressure in the container 70. Adjacent the passageway 74, there is an expandable slit 90 in the walls of the pocket 75. Excess pressure causes fluid to be forced through the slit 90 into an annular recess 91 formed in the adapter 84 and out into the atmosphere through the outlet port 92 in the walls of the adapter 84. The flow path of the fluid is graphically illustrated by the arrowed line.

FIGS. 9 and 10 illustrate in cross-section portions of pressurized fluid containers having valve structure fittings also shown in cross-section embodying the principles of the present invention. In one case, FIG. 9, the opening to the container 10 is formed integrally with the side walls of the container such as by a drawing operation. In FIG. 10, the can body is first formed and has secured to it a cap portion 100 which includes an opening through which the valve is inserted. The valve body 16 is accommodated by the opening in pressure withstanding engagement.

In other respects, the valves shown in FIGS. 9 and 10 are quite similar to the valves shown in FIGS. 2 and 6, respectively. The valve structures in FIGS. 9 and 10 are each provided with valve stems 30 having an axial bore 35 communicating with a radial bore 37 on the low pressure side of valve 34. Valve 34 seats against valve seat 23 which is contained integrally with the housing 16 and disposed around the outlet 21 therein. Valve stem 30 is provided with an annular recess 38 adapted to receive fluid passing between the valve 34 and the valve seat 38 for distribution to the radial port 37 and ultimate exit from the container through outlet or axial bore 35.

Each of the structures in FIGS. 9 and 10 includes a fluid receiving chamber 22 integrally formed in the housing 16 and having resilient side walls as hereinbefore described. An abutment portion 26 integral with housing 16 includes an abutment 24 against which valve stem extremity 32 is resiliently biased. In the case of FIG. 9, fluid entry into fluid receiving chamber 22 is gained by the apparatus shown in FIG. 2 and including a flexible tube 41 communicating with an extension 35a of axial bore 35 which in turn communicates with the chamber 22 through the radial bore 36. The side wall of chamber 22 will be also provided with a slit as the slit in 50a (FIG. 6) in order to provide for refilling of the container. A

fluid-tight seal is effected between the walls of passage-way 21 in housing 16 and valve stem 30 so that the fluid is forced to exit from the container through the passage-way 35. Although valve stem 30 is axially slideable in the opening 21 to provide for unseating of the valve 34, nevertheless the seal between opening 21 and valve stem 30 is able to withstand pressure exerted by the internal contents.

In FIG. 10 access to chamber 22 is gained through opening 49 in the side wall thereof. Hence, an axial bore extension such as shown in FIG. 9 on the high pressure side of the valve 34 is unnecessary and the valve stem extension 31a serves to provide an abutment 32 for coaction with the abutment 24 formed in the wall of chamber 22 at its innermost extremity.

In the structure shown in FIG. 10, the valve structure may be combined with the cap portion 100 before assembly of the cap portion to the can either by rolling or soldering to the can body 10. Alternately, and in many cases advantageously, the entire metallic portion of the can body may be assembled at a can making facility, and the valve structures of the present invention inserted at the site of filling the containers. This is often a remote place from the source of the finished can bodies. Filling of pressurized containers is normally accomplished by introducing the contents through the opening defined by the radially inwardly extending flange 101 at a temperature below the boiling point of the propellant material e.g. -40° F. so that the contents of the containers may be handled easily in the liquid state at atmospheric pressure. After introducing the contents the valve structures of the present invention may be forcibly inserted into the opening at the top of the container and into pressure withstanding engagement therewith. When the contents return to room temperature, pressure is developed in the container and the contents may be released by unseating valve 34 from valve seat 23 using the externally accessible valve stem 30.

FIG. 11 shows an embodiment of this invention which is similar to that shown in FIG. 2. In this embodiment, however, the valve stem 38 is recessed relative to opening 21 for a greater axial distance than shown in FIG. 2. Closely adjacent the valve seat 23 there is provided a secondary seal 105 in the form of an annular constriction in opening 21 so shaped and dimensioned to coact in sliding engagement with the stem 38 much like a ring seal. Radial port 37 is normally located between the seal 105 and the valve seat 23. External annular rim 106 coacts between plug portion 17 and shoulder 43 to provide additional sealing and biasing means tending to seat valve 34 against the valve seat 23. The structure of FIG. 11 provides adequate sealing and offers less resistance to valve stem movement.

Thus there has been provided a new and novel combination dispensing and fluid relief valve used in a pressurized container, wherein the contents of the container are discharged by manually depressing the stem of the valve. The resilient housing, designed to take the place of a multiplicity of springs used in other devices, biases the valve in a closed position. The parts are relatively simple and easily replaced and are also economically produced.

Other modes of applying the principle of this invention may be employed instead of those specifically set forth above, changes being made as regards the details herein disclosed, provided the elements set forth in any of the following claims, or the equivalent of such be employed.

It is, therefore, particularly pointed out and distinctly claimed as the invention:

1. A dispensing valve structure for a pressurized fluid container comprising in combination:

- (a) a resiliently flexible member enclosing a chamber;
- (b) a fluid outlet from the chamber in said member;
- (c) a valve seat surrounding said outlet;

5 (d) a fluid inlet to the chamber in said member spaced from said outlet;

(e) an externally accessible rigid valve stem extending into the chamber through said fluid outlet into engagement with an internal portion of said member said stem being of such a length so as to engage the bottommost end of said chamber for deflecting the entire chamber enclosing resilient member;

(f) a valve carried by said stem and biased by said flexible member into seating outlet closing engagement with said valve seat; whereby movement of the valve stem against the engaged portion of said member will resiliently deflect the entire flexible member, unseat the valve, and open the outlet to control the dispensing of fluid through said chamber.

10 2. A dispensing valve structure for a pressurized fluid container having an opening therein comprising in combination:

- (a) a resiliently flexible valve housing;
- (b) a wall enclosed chamber integral with said housing;
- (c) an abutment in one end of said housing and integral therewith;
- (d) a plug adapter portion at the other end of said housing and integral with said housing and adapted to fit in a container opening;
- (e) fluid inlet passage means for transmitting pressurized fluid into said chamber;
- (f) fluid outlet passage means for transmitting fluid from the chamber;
- (g) a valve seat surrounding said outlet passage means;
- (h) a rigid elongated externally accessible valve stem reciprocably extending through said plug portion and said chamber into abutting relation with said abutment; and
- (i) a valve carried by said valve stem and disposed for seating coaction with the valve seat; said valve stem adapted to coact with said abutment in said housing to elastically deform the entire housing and unseat the valve.

15 3. A dispensing valve structure in accordance with claim 2 in which the valve stem coacts with the plug portion to form a pressure withstanding seal therewith.

4. A dispensing valve structure for a pressurized fluid container having an opening therein comprising in combination:

- (a) a resiliently flexible valve housing;
- (b) a wall enclosed chamber integral with said housing;
- (c) an abutment in one end of said housing and integral therewith;
- (d) a plug adapter portion at the other end of said housing and integral with said housing and adapted to fit into the container opening for frictional engagement thereby;
- (e) excessive pressure relief means in said plug portion;
- (f) fluid inlet passage means for transmitting pressurized fluid into said chamber;
- (g) fluid outlet passage means for transmitting fluid from the chamber;
- (h) a valve seat surrounding said outlet passage means;
- (i) a rigid elongated externally accessible valve stem reciprocably extending through said plug portion and said chamber into abutting relation with said abutment; and
- (j) a valve carried by said valve stem and disposed for seating coaction with said valve seat; said valve stem adapted to coact with said abutment in said housing to elastically deform the entire housing and unseat the valve.

70 5. A dispensing valve structure in accordance with claim 4 in which the excessive pressure relief means in-

cludes an annular groove in the under side of said plug portion.

6. A dispensing valve structure in accordance with claim 4 in which the fluid inlet passage means includes an aperture in the wall of the wall enclosed chamber adapted to pass fluid between the container interior and the chamber. 5

7. A dispensing valve structure in accordance with claim 4 in which the wall enclosed chamber includes a slit in the wall of the wall enclosed chamber adapted to pass fluid between the chamber and the container interior. 10

8. A dispensing valve structure in accordance with claim 4 in which the fluid inlet passage means includes an axial bore extending through the abutment and communicating with a fluid conduit in the valve stem opening into said chamber. 15

9. A dispensing valve structure in accordance with claim 4 in which the valve seat is an annular shoulder surrounding the fluid outlet.

10. A dispensing valve structure in accordance with claim 9 in which the valve is an annular shoulder carried by said valve stem and is complementarily configured for seating coaction with said annular valve seat. 20

11. A dispensing valve structure for a pressurized fluid container having a circular opening therein comprising in combination: 25

(a) a resiliently flexible valve housing;
(b) a plug portion at one end of said housing having a diameter larger than the circular opening in said container and defining a shoulder extending over a portion of the exterior of the container; 30

(c) a wall enclosed chamber depending from said plug portion and integral therewith and having a diameter larger than the circular opening in said container but less than the diameter of said plug portion; 35

(d) an abutment portion in one end of said housing and depending from said wall enclosed chamber;

(e) fluid inlet passage means for transmitting pressurized fluid into said chamber;

(f) fluid outlet passage means for transmitting fluid from said chamber; 40

(g) a valve seat surrounding said outlet passage means;
(h) a rigid elongated valve stem reciprocably extending through said plug portion and said wall enclosed chamber into abutting relation with said abutment portion; and 45

(i) a valve carried by said valve stem and disposed for seating coaction with said valve seat;
said valve stem adapted to coact with said abutment in said housing to elastically deform the entire housing and unseat the valve. 50

12. A dispensing valve structure in accordance with claim 11 wherein said plug portion includes an annular recess in the surface of the shoulder thereof from which the wall enclosed chamber portion depends.

13. A closure top for a metallic container of pressurized dispensable fluid comprising in combination:

(a) a metallic closure member adapted to be secured to an opening in the top of said container;

(b) a circular opening centrally disposed in said closure member;

(c) a dispensing valve structure frictionally engaged in the circular opening in said closure member, said dispensing valve structure including;

(d) a resiliently flexible valve housing;

(e) a wall enclosed chamber integral with said housing;

(f) an abutment in one end of said housing and integral therewith;

(g) a plug adapter portion at the other end of said housing and integral with said housing and adapted to fit in a container opening; 70

(h) fluid inlet passage means for transmitting pressurized fluid into said chamber;

(i) fluid outlet passage means for transmitting fluid from the chamber; 75

(j) a valve seat surrounding said outlet passage means;
(k) a rigid elongated externally accessible valve stem reciprocably extending through said plug portion and said chamber into abutting relation with said abutment; and

(l) a valve carried by said valve stem and disposed for seating coaction with the valve seat;
said valve stem adapted to coact with said abutment in said housing to elastically deform the entire housing and unseat the valve.

14. A closure top for a metallic container of pressurized dispensable fluid comprising in combination:

(a) a metallic closure member adapted to be secured to an opening in the top of said container;
(b) a recess centrally disposed in said closure member;

(c) a circular opening having a diameter less than the diameter of said recess extending through the bottom of said recess;

(d) a dispensing valve structure frictionally engaged in the circular opening in said closure member, said dispensing valve structure including;

(e) a resiliently flexible valve housing;

(f) a wall enclosed chamber integral with said housing;

(g) an abutment in one end of said housing and integral therewith;

(h) a plug adapter portion at the other end of said housing and integral therewith and so dimensioned as to frictionally engage the said walls of said recess;

(i) fluid inlet passage means for transmitting pressurized fluid into said chamber;

(j) fluid outlet passage means for transmitting fluid from the chamber;

(k) a valve seat surrounding said outlet passage means;

(l) a rigid elongated externally accessible valve stem reciprocably extending through said plug portion and said chamber into abutting relation with said abutment; and

(m) a valve carried by said valve stem and disposed for seating coaction with the valve seat;
said valve stem adapted to coact with said abutment in said housing to elastically deform the entire housing and unseat the valve.

15. A closure top for a metallic container in accordance with claim 14 in which the external surfaces of the wall enclosed chamber have a diameter larger than the chamber of the circular opening, said walls being deformed by said circular opening.

16. A closure top for a metallic container in accordance with claim 14 in which the plug adapter portion includes an annular recess defining a circular channel with the bottom of the recess in said metallic closure member.

17. A closure top for a metallic container in accordance with claim 16 in which the bottom of the recess in the metallic closure member includes fluid exit means for excessive pressure relief, said fluid exit means communicating with said annular recess in said plug adapter portion.

18. A closure top for a metallic container of pressurized dispensable fluid comprising in combination:

(a) a metallic closure member adapted to secure to an opening in the top of said container;

(b) a recess extending inwardly of the container and centrally disposed in said metallic closure member;

(c) a circular opening having a diameter smaller than the diameter of said recess portion, said opening disposed in the bottom of said recess;

(d) a plurality of circumferentially spaced holes in the bottom of said recess surrounding said circular opening;

(e) a dispensing valve structure frictionally engaged in the circular opening in said closure member, said dispensing valve structure including;

(f) a resiliently flexible valve housing;

11

- (g) a wall enclosed chamber integral with said housing;
- (h) an abutment in one end of said housing and integral therewith;
- (i) a resilient plug adapter portion at the other end of said housing and integral with said housing having a diameter slightly larger than the diameter of said recess and adapted to frictionally remain engaged therein;
- (j) fluid inlet passage means for transmitting pressurized fluid into said chamber;
- (k) fluid outlet passage means for transmitting fluid from the chamber;
- (l) a valve seat surrounding said outlet passage means;
- (m) a rigid elongated externally accessible valve stem reciprocably extending through said plug portion and said chamber into abutting relation with said abutment;
- (n) a valve carried by said valve stem and disposed for seating coaction with the valve seat;
- (o) a discontinuous axial bore extending inwardly from each extremity of said valve stem, but not extending through said valve stem;
- (p) a radial bore communicating between the inner end of one of said axial bores and the surface of the valve stem on one side of the valve;
- (q) a separate radial bore communicating between the inner extremity of the other of said axial bores and the surface of said valve stem on the other side of said valve; and
- (r) a portion of said valve stem of reduced diameter on the low pressure side of said valve defining in combination with the outlet passage a second fluid receiving chamber, said radial bore positioned so as to be in communication with said second fluid receiving chamber;
- 19. A dispensing valve structure for a pressurized fluid container having a circular opening therein comprising in combination:
- (a) a resiliently flexible valve housing;
- (b) a plug portion at one end of said housing having a diameter larger than the circular opening in said container and defining a shoulder extending over a portion of the exterior of the container, and including an axial bore;
- (c) a wall enclosed chamber depending from said plug portion and integral therewith and having a diameter larger than the circular opening in said container but less than the diameter of said plug portion;
- (d) an abutment portion in one end of said housing and depending from said wall enclosed chamber;
- (e) fluid inlet passage means for transmitting pressurized fluid into said chamber;
- (f) fluid outlet passage means for transmitting fluid from said chamber;
- (g) a valve seat surrounding said outlet passage means;
- (h) a rigid elongated valve stem reciprocable in said axial bore extending through said plug portion and said wall enclosed chamber into abutting relation with said abutment portion and having a diameter less than the diameter of said bore;
- (i) a constriction in said axial bore axially spaced from said valve seat and dimensioned for sliding sealing engagement with said valve stem; and
- (j) a valve carried by said valve stem and disposed for seating coaction with said valve seat;
- said valve stem adapted to coact with said abutment in said housing to elastically deform the entire housing and unseat the valve.
- 20. A dispensing valve structure for a pressurized fluid container comprising in combination:

12

- (a) a resiliently flexible member enclosing a chamber;
- (b) a fluid outlet from the chamber in said member;
- (c) a valve seat surrounding said outlet;
- (d) a fluid inlet to the chamber in said member spaced from said outlet;
- (e) an externally accessible rigid valve stem extending into the chamber through said fluid outlet into abutting engagement with an internal portion of said member said stem being of such a length so as to engage the bottommost end of said chamber for deflecting the entire chamber enclosing resilient member;
- (f) a valve carried by said stem and biased by said flexible member into seating outlet closing engagement with said valve seat whereby movement of the valve stem against the engaged portion of said member will resiliently deflect the entire flexible member, unseat the valve, and open the outlet to control the dispensing of fluid through said chamber;
- (g) a pair of inwardly directed axial bores in said valve stem;
- (h) each of said axial bores communicating with a radial bore through the side wall of said stem, said radial bores being spaced apart and on opposite sides of said valve; and
- (i) one of said axial bores cooperating with said inlet to supply fluid under pressure to said chamber, and the other cooperating with said outlet to exhaust fluid from said chamber in response to movement of the valve stem against said flexible member.
- 21. A dispensing valve structure for a pressurized fluid container comprising in combination:
- (a) a resiliently flexible member enclosing a chamber;
- (b) an elongated fluid outlet from the chamber in said member;
- (c) a plurality of spaced valve seats located along a common axis surrounding said outlet;
- (d) a fluid inlet to the chamber in said member spaced from said outlet;
- (e) an externally accessible rigid valve stem extending into the chamber through said fluid outlet into engagement with an internal portion of said member said stem being of such a length so as to engage the bottommost end of said chamber for deflecting the entire chamber enclosing resilient member;
- (f) a plurality of axially spaced valves carried by said stem and biased by said flexible member into seating outlet closing engagement with each of said valve seats;
- whereby movement of the valve stem against said flexible member will resiliently deflect the entire flexible member, simultaneously unseat each valve to open the outlet to permit dispensing of fluid from said chamber.
- 22. A dispensing valve structure for a pressurized fluid container having an opening therein comprising in combination:
- (a) a resiliently flexible valve housing;
- (b) a wall enclosed chamber integral with said housing;
- (c) an internal abutment in one end of said housing and integral therewith;
- (d) fluid inlet passage means for transmitting pressurized fluid into said chamber;
- (e) fluid outlet passage means for transmitting fluid from said chamber;
- (f) a plug adapter portion at the other end of said housing, integral with said housing, adapted to seat in a container opening, and having a cylindrical bore extending therethrough for communication with said fluid outlet;
- (g) a valve seat surrounding said outlet passage means;
- (h) a rigid elongated externally accessible valve stem reciprocably extending through the bore in said plug

portion and said chamber into abutting relation with said abutment, said valve stem adapted to coact with said abutment in said housing to elastically deform the entire housing;

- (i) a valve carried by said valve stem biased by said housing and disposed for seating coaction with said valve seat and adapted to be unseated when said valve stem elastically deforms said housing;
- (j) said valve stem including a cylindrical portion dimensioned to sealingly engage the walls of said cylindrical bore through said plug portion to form a pressure withstanding seal therewith.

23. A dispensing valve structure in accordance with claim 22 in which the cylindrical bore of said plug portion

includes an annular recess and defines axially spaced stem engaging collars coacting with said valve stem to form axially spaced pressure withstanding seals therewith.
